PACKAGE TREATING MACHINE

Frederick E. Bickford, Rye, N. Y.

Application April 4, 1938, Serial No. 199,860

28 Claims. (Cl. 226—68)

This invention relates to means for applying vacuum or suction to the chain links of a conveyor mechanism. Particularly, it relates to the application of vacuum or suction to the carrier links of a package treating or evacuating machine and to the packages or containers carried thereby.

5 An object of the invention is to provide a machine in which suction is continuously applied to the links of a conveyor chain with a minimum of leakage at any point.

10 Another object of the invention is to provide positive driving means for the chain links, synchronized with valve means for admitting suction 15 to the links.

A further object of the invention is to apply 20 a gas at or above atmospheric pressure to the evacuated container subsequent to the application of the vacuum.

25 Further objects and features of the invention will appear when the following specification is considered in connection with the annexed drawings, in which,

Figures 1 and 2, taken together, form a side view of a machine embodying the evacuating and 30 pressure applying mechanism. This mechanism is utilized to evacuate containers during continuous movement of the links of a chain in airtight compartments of which the containers are carried; and to fill the evacuated containers with gas under atmospheric or other pressure;

Figure 3 is a transverse, cross-sectional view taken along the line 3—3 of Figure 2, showing a portion of the driving mechanism;

Figure 4 is a longitudinal, cross-sectional view 35 of the left hand portion of the machine of Figures 1 and 2;

Figure 5 is in part a broken, longitudinal section of the machine of Figures 1 and 2, the section being taken off center, and is in part a side elevation of a portion of the machine on a 40 larger scale than that of Figures 1 and 2;

Figure 6 is a transverse, cross-sectional view taken on the line 6—6 of Figure 4;

Figure 7 is a transverse, cross-sectional view 45 taken on the line 7—7 of Figure 4;

Figure 8 is a fragmentary elevation of the right hand portion of the machine showing the connection of the pressure source to the machine, and showing likewise a modification and 50 addition to the means for synchronizing the movement of the chain links with the controlling valve structure and the means for automatically opening and closing the evacuating chambers. This figure also shows one mode of capping a container which has been evacuated and then filled with gas under pressure;

Figure 9 is a fragmentary, transverse, cross-sectional view of the mechanism of Figure 8, 55 taken along the line 9—9 of that figure;

Figure 10 is a fragmentary end view of the upper portion of the evacuating chamber of Figure 8 showing the means for latching the door in closed position;

Figure 11 is a side view of the mechanism of 5 Figure 10;

Figure 12 is a view similar to that of Figure 11 showing the latching means in operated position;

Figure 13 is a view generally similar to Figure 4 10 but showing a different form of valve mechanism and a slightly modified form of link structure. In addition, this view shows details of a structure for assuring vacuum-tight relationship of the links with the outer valve tube during 15 a portion of the suction application;

Figure 14 is a fragmentary, transverse, cross-sectional view on the plane of line 14—14 of Figure 13 showing the valve mechanism of Figure 13 in relation to the supporting structure; 20

Figure 15 is an enlarged cross-sectional view of one of the poppet valves utilized in the mechanism of Figures 13 and 14;

Figures 16 and 17 are, respectively, enlarged 25 top and bottom plan views of the poppet valve of Figures 13 and 14 showing further details of its construction;

Figure 18 is a transverse, cross-sectional view on the plane of the line 14—14 of Figure 13 showing the construction of a modified form of 30 link structure;

Figure 19 is a side elevation, with the outer plate removed, of the link of Figures 13 and 18;

Figure 20 is a fragmentary side view of a package treating machine generally similar to that 35 of Figures 1 and 2, but having a modified driving mechanism for causing intermittent movement of the links. This view also shows a modified closure applying structure adapted to be used with this modified driving mechanism; and

Figure 21 is a plan view of the modified driving mechanism of Figure 20 taken on the plane 40 of the line 21—21 of that figure.

This application is a continuation in part of my co-pending application Serial No. 155,215, 45 filed July 23, 1937, for Packaging, package making, and package treating machines. That portion of the following description dealing with Figures 13 to 21 is new in this application; all other material has been taken directly from the 50 earlier application.

Supporting structure

The various moving parts of this machine are supported upon a frame structure which comprises two casings 101 and 201 (Figs. 1 and 2) joined together at their bases by the angle members 38, and at their tops by the channel members 39, 40 and 41, the two outer ones of which (Fig. 6) rest on their flanges, and the middle one 60

of which rests on its base. The two outer channels 39 and 41 extend considerably beyond the castings 101 and 201, and are supported at their extreme ends by the inclined angle members 103, 5 104, and 203, 204, which are fastened to the castings by means of plates as 102 and 202. The center channel 40 extends but slightly beyond the supporting castings; it is supported at each end by one of the short channel members 105 and 10 205, extending to a bracket 106 or 206 bolted to the casting.

Spaced along the channel members at any desired intervals are castings as 42, 43 and 44 which rest on the upturned bases of the outer channels 15 39 and 41, and are so shaped as to protrude within the channel member 40. Supported by the castings 42, 43 and 44, through the medium of compression springs 46, which are within vertical bores in the castings (Fig. 7) 42, 43 and 44, is 20 the valve mechanism support 47. The compression springs 46 are adjustable by means of plungers 48 (Figs. 5, 6 and 7) screwed into the castings. The support 47 is guided in its vertical movement by means of guide pins 49 (Fig. 6), 25 which pins are driven into castings 42, 43 and 44 and extend into corresponding holes in support 47. These pins 49 prevent movement of support 47 either longitudinally, transversely, or rotationally, while permitting vertical movement thereof.

30 The support 47 is generally semi-cylindrical and has fitted into its semi-cylindrical upper surface a tube 50 which forms the guide or track for the links of a moving chain as will be described hereinafter. In the form of the invention 35 illustrated in Figures 1 and 2 a second tube 51 which has, in its outer surface, a helical groove cooperating with holes in the exterior tube to form means for controlling the application of vacuum or pressure to the moving links, as will 40 be described hereinafter, is rotatable within the with the tube 50.

Supported near the ends of the outer channel members 39 and 41 are two castings 110 and 210 (Figs. 1 and 2), each of which is supplied with a plurality of bearing blocks which rotatably support the four shafts 52, 53, 54 and 55, which 45 shafts extend longitudinally of the machine. Shafts 52 and 54 pass through the castings 42, 43 and 44, being freely rotatable in semi-cylindrical bushings inserted in holes in the castings and 50 thus supported by the bushings against upward pressure. Shafts 53 and 55 are supported in bearing blocks 135, 136, 235, 236, fastened to the castings 101, 201. The upper shafts 52 and 54 55 are helically grooved throughout the distance between castings 42 and 44 in order to control the movement of the chain links, as will appear hereinafter. Shafts 52 and 54 are arranged to be driven respectively from shafts 53 and 55 in a manner which will be discussed under the heading 60 "Chain driving mechanism".

Chain driving mechanism

The driving mechanism for the conveyor chain 65 may be in either of two forms, one providing for continuous and the other for intermittent movement. Certain of the mechanism is common, as will be pointed out hereinafter. In the first form of the mechanism there are at each end of the 70 machine (Figs. 1, 2 and 6), two sprockets 111, 112 and 211, 212, the periphery of each of which is polygonal in shape. These sprockets drive a continuous chain which is formed of the links 56, which links are shaped to form a vacuum seat 75 with the tube 50.

The sprockets 111, 112 are supported on the shaft 113 which is in turn rotatably supported in a bushing 114, (Figs. 4 and 6), which is fastened to the inclined channel member 105. On the outer end of the shaft 113, a gear wheel 115 is 5 fastened. It will appear, therefore, that as the gear wheel 115 is driven, it in turn turns the shaft 113, causing the sprockets 111, 112, fixed thereto, to rotate and to move the links of the chain continuously.

10 The movement of sprockets 211 and 212 is transmitted to the gear wheel 215 and shaft 213, which shaft is similarly supported by bearing block 214 fastened to the channel member 205.

Adjacent the casting 101 and supported therefrom through the medium of the auxiliary castings 116, 117, and bearing blocks 116', 117' (one on either side of the machine) is a shaft 118 which carries a pulley wheel 123 and small pinion 119 at one end, a gear wheel 120 at the other end, 20 and two worms 121 and 122 (one adjacent either end). The pinion 119 meshes with the gear wheel 115 in order to supply power for driving the sprocket wheels as described. Power is applied to the shaft 118, through the medium of 25 the pulley wheel 123, belt 124, and motor 109, which motor is fastened to the angle members 38 of the frame structure.

At the right hand end of the machine, looking 30 at Figs. 1 and 2, a similar shaft arrangement is provided, comprising a shaft 218 carrying the worms 221 and 222, the gear 220, the pinion 219, and a pulley 223, power being supplied to this end of the machine through a belt 224 (Figs. 1 and 2) as well as through the shafts mentioned 35 above, and considered in detail hereinafter.

As is best shown in Fig. 3, shaft 52 has fixed 40 thereon a gear 225; shaft 53, gear 226; shaft 54, gear 227; and shaft 55, gear 228. Gear 226 drives gear 225 through the medium of idler gear 229 which rotates on the stub shaft 230, fixed to the casting 210. Similarly, gear 228 drives gear 227 through the medium of idler gear 231, mounted on the stub shaft 232, likewise fixed in the casting 210.

At the left hand end of the machine, similar 45 idler gears 129 and 131 mounted on stub shafts 130 and 132 are provided to drive gears 125 and 127, the idlers being themselves driven by gears 126 and 128.

Lower longitudinal shafts 53 and 55 have 50 mounted thereon near their left ends worm wheels 133 and 134 and at their right ends worm wheels 233 and 234 which mesh with the worms 121, 122, 221 and 222 previously described, thus providing means for driving the various longitudinal 55 shafts of the machine.

Chain links

Each chain link 56 comprises a body portion 60 57 having a longitudinal semi-cylindrical groove in the base thereof (Figs. 6 and 7), which groove is adapted to form a vacuum or pressure-tight seal with the outer valve tube 50. Each base portion 57 has fastened thereto two side members 65 58 and 59 which extend downwardly and outwardly, and are stepped along their lower edges to cooperate with similarly stepped surfaces of the valve support 47. The lower, outer surfaces of the members 58 and 59 are guided for vertical 70 movement by the guide rails 60 and 61, which guide rails extend longitudinally of the machine and are fixed in the castings 42, 43 and 44. The upper faces of the downward extremities of the side members 58 and 59 are curved to fit the 75

outer surfaces of the helically cut shafts 52 and 54.

Extending through the base portion 57 of each chain link is a passage-way 62 which communicates with the chamber formed above the base by the housing 63 and the air-tight door 64. As will be hereinafter described, means are provided for holding the door 64 in closed position during evacuating and pressure applying operations and for opening the door in order to permit placement of a container in the compartment, and removal of the container therefrom at the completion of operation.

It will be seen from the description previously given that springs 46 push the valve or tube support 47 upward against the bottom of the outer valve tube 50, said tube 50 pushing upward against the bottom of the base portion 57 of the link 56 which in turn holds the curved upper faces of the extensions 58 and 59 up against the underside of the helically cut shafts 52 and 54, thus assuring a vacuum-tight joint between the links 56 and the outer valve tube 50.

Means are likewise provided to assure a tight joint between the outer tube 50 and inner tube 51, this means comprising an arcuate plate 65 (Fig. 7) which extends for substantially the entire length of the support 47 along the bottom thereof, the outer tube 50 being cut away to accommodate this plate. Screwed into the support 47 at spaced intervals along the bottom thereof are cylindrical spring holders 66 which are closed at their ends by cap nuts 67 screwed on the outside of the holder. The plugs 67¹ screwed inside the lower end of the holders regulate the pressure of the springs 68, within the tubes, against the member 65. The screw joints between the support 47 and the spring holders 66, as well as the screw joints between holders 66 and nuts 67, are hermetically sealed to prevent any loss of vacuum or pressure through these members. Due to the construction just mentioned, the inner tube 51 is kept in vacuum-tight register with the outer tube 50, thus assuring that there shall be no leakage of vacuum or pressure from the outside atmosphere into the evacuated or pressure chambers. As wear takes place the springs compensate therefor and maintain the vacuum-tight register.

Side members 58 and 59 of each link are slotted 50 at their forward ends (Figs. 4 and 6) to fit over rearward extensions of adjacent link side members so that the rearward end of each link side piece may extend into the slot of the link following, thus forming the continuous chain which 55 is a feature of the machine. After the rearward extensions of the link pieces are positioned in the slotted forward portions, screws are passed through holes in the forward slotted portions and the extensions to pivotally connect the links together. This link construction is best shown in Fig. 6 wherein the slotted forward portions and narrow rearward extensions of the side members are clearly shown in section at 69 and 70, 71 and 72, respectively, the shouldered pivot 65 screws being shown at 73 and 74.

Extending outwardly from each side piece 58, 59, on a line through the center of shaft 52 or 54, is a stud carrying a roller adapted to fit the helical groove of the corresponding shaft.

70 The rollers cooperate with the respective shafts 52, 54 to assure the correct rate of movement of the links 56 with respect to the rotation of the helically grooved inner tube 51 and in addition are mounted on the side members 58 and 59 in such manner that the rotation of the shafts tends

to seat the body portion 57 of the links squarely and solidly on the outer valve tube 50.

Vacuum control mechanism

As has been stated, the moving links 56 are 5 adapted to the application of either vacuum or pressure to the chambers forming part of these links, the vacuum or pressure being continuously applied during the movement of the links through portions of their cycle, and in one form of the 10 invention augmented by increasing the seating pressure during intervals when the chain is not in motion as is described hereinafter.

The two tubes 50 and 51 already mentioned 15 cooperate to control the application of vacuum or pressure to the moving links, the pitch of the helical groove in the inner tube relative to the spacing of holes in the outer tube assuring the continuous application of a vacuum or pressure to the links as they are moving in the path described. The mode of supporting these tubes has already been described; the mode of applying vacuum or pressure thereto, and the means for rotating the inner tube remain to be described.

Referring now to Fig. 4, it will be seen that the 25 inner tube 51 is provided with a helical groove 51a, the pitch of the helix on which the said groove is cut being such that one complete turn of the helix occurs in a distance equal to that between the centers of two successive chain links 80 56 and the width of the groove being such that it covers two adjacent holes in the outer tube 50. Also the passage 62 covers two adjacent holes in tube 50. In other words, the center of the surface between successive turns of the helix always lies 35 midway between the centers of two successive chain links. Therefore, any link is constantly in communication with the inner valve tube, and the flat surfaces between turns of the helix always bear against the surfaces between the openings, thus shutting off the spaces between successive chambers.

At intervals along the helical groove there are 45 holes 51b connecting the groove with the interior of the tube so that vacuum drawn through the center of the tube will cause evacuation of the groove and through it and the holes in the stationary tube 50 cause evacuation of the chambers of the links 56.

If the material in the containers is finely powdered or of like nature and likely to be removed from the container by sudden application of the suction, then the holes in outer valve tube 50 may be smaller at the left end of the machine, thus causing gradual application of the suction.

Inserted in the left end of the inner tube 51 is a short section of slightly smaller tubing 141 which is fastened to tube 51 by rivets or pins 142 and which has a reduced portion at the left end thereof. The inner tube 51 terminates slightly 60 to the right (Fig. 4) of the left end of tube section 141.

In the outer tube 50 and abutting the end of inner tube 51 is a tube 143 having an integral flange at its left hand end. This flange is ground to form a conical seat for a conically flanged, rotatable member hereinafter described.

Fastened to the channel 40 near its left end (Figs. 4 and 6) by means of screws 144, is a block 70 145 which supports a casting 146. The casting 146 has an upward portion which is flared out to form a semi-circular block adapted to fit within and support the extreme left end of the outer valve tube 50, which tube has a wide cut at its 75

base at the end. The tube 50 is fastened to casting 146 by means of screws 147.

Casting 146 is held in place on block 145 by pins 148 which permit vertical movement only.

5 As wear takes place shims may be inserted between the block and casting in order to compensate therefor.

The casting 146 also serves to support a pipe elbow 151, one end of which is connected to pipe 10 152, which in turn is flexibly connected to a vacuum pump or other source of negative pressure (not shown). The other end of pipe elbow 151 communicates with the interior of valve tube 51 in the manner about to be described.

15 Projecting from the side of a vertical portion of pipe elbow 151 is a pin 153 which slidably fits within a hole in the casting 146 to guide the elbow for limited horizontal movement.

Projecting from the pipe elbow 151 along its 20 horizontal center line is a second pin 154 which extends within a cylinder 155 fitted into a bore in the upper portion of casting 146 and which is held in position by set screw 156. Within the cylinder 155 is a compression spring 157 which is 25 compressed against the end of pin 153 by means of screw 158 which threads into the cylinder at its left end and bears against the spring.

The horizontal portion 159 of the pipe elbow 151 extends to the right and is beveled at its end 30 to form a seat for the correspondingly beveled hub of a worm wheel 165. In the left hand face of this worm wheel is a circular grooved bearing member 166 in which runs a spring thrust and centralizing member 167. This member 167 is 35 held in the grooved bearing 166 by means of a spring 168, the other end of which bears against a flange 169 on the pipe elbow 151.

40 Worm wheel 165 has a tubular portion projecting to the right and fitting into the internal bore of a tube 170, which has a conical outer surface which fits the conical seat mentioned above. The tube 170 is caused to rotate with the worm wheel 165 by means of a pin 171 extending through the two members. To the right of the 45 conical flare on the member 170 is a short cylindrical hub portion which extends within the tube section 141 and which is connected to tube 141 for rotation thereof by means of pin 172 extending through holes in member 170 and into arcuate slots in tube 151.

50 It will be seen from the description given that the conical member 170 is caused by the spring 168 to bear against the conical seat formed on tube 143 and the spring 157 holds the beveled end of the 55 portion 159 against the conical seat of the beveled hub of the worm wheel 165 to maintain vacuum-tight joints through which air can be evacuated from the interior of tube 51 by means of the vacuum pump or other source of suction. It will 60 likewise be seen that rotation of worm wheel 165 causes rotation of tube or tube sections 170, 141 and 51. As has been described, tube 51 is spring-pressed upwardly to bear against the upper, inner surface of tube 50. It is because of this that tube 65 section 141, and the hub portion of member 170, are joined for rotation by pin 172 which permits slight movement of inner tube 51 to care for wear.

Driving means for the valve tube

70 As has been indicated, the valve tube 51 must be driven synchronously with the chain sprockets 111, 112, 211, 212, and with the helically grooved shafts 52, 54. For this purpose a worm 175 is provided, which worm is mounted on a shaft 176 (Figs. 4 and 6) for rotation therewith. Shaft 176

is supported for rotation by bearing blocks 178 and 179 screwed to the casting 42. Fixed to shaft 176 at its left hand end is a gear 177 which meshes with the gear 120 fixed to the shaft 118. Shaft 118 is rotated in the manner previously described. 5

At the right hand end of the machine shown in Figs. 2, 5 and 8, a substantial duplicate of this arrangement is provided, the only difference being that the construction of the conical seat and valve member is altered to provide for pressure 10 rather than vacuum. The driving equipment is, however, exactly similar. Referring now to Fig. 8, worm wheel 265 drives the right hand portion of the inner tube 51 in a manner similar to that in which worm wheel 165 drives the left hand portion 15 of the tube. Worm wheel 265 is driven by worm 275 mounted on shaft 276 supported in bearings 278 and 279. Shaft 276 is driven by gear 277 meshing with gear 220 on shaft 218.

It is, of course, possible to evacuate containers 20 without thereafter admitting gas under pressure to those containers. If this is to be done, the tube 51 is continuous from one end of the machine to the other, and the valve arrangements at the two ends are exactly similar, or the tube is blocked 25 at one end, as is preferable. Under these circumstances, the two worm wheels 165 and 265 simply drive the one tube 51 and prevent any twisting of 30 that tube by their synchronous operation, one on either end. 35

Pressure control mechanism

When the containers are to be evacuated and then filled with gas, the tube 51 is made in two pieces, a plug being inserted substantially in the 35 middle of the outer tube 50. This plug is shown in Fig. 5 and is designated 280. It is inserted in the tube 50 by heating tube 50 and cooling the plug, threading a long rod into the screw thread 281 of the plug, and pushing the plug to the desired point in tube 50. As the plug 280 and tube 50 reach the same temperature, the plug will have expanded, and the tube contracted, to form a vacuum and pressure-tight joint so that there will be no leakage from one portion of tube 51 to the 40 other. The rod used for inserting the plug is then removed. When this plug is inserted there are two separate inner tubes 51; also a central portion of outer tube 50 is left solid so that for an 45 instant there is no application of either vacuum or pressure to the link chambers (Fig. 5). 50

Coming now to the valve structure utilized when this pressure application is to take place, reference is made to Fig. 8 in which a structure similar to that of Fig. 4 is shown, modified, however, as indicated. 55

Fastened to the channel 40 is a block 245 which supports a casting 246. The casting 246 has an upward portion which is flared out to form a semi-circular block adapted to fit within and support the extreme right end of the outer valve tube 50. The lower portion of the tube 50 is cut away in order to provide space for the various parts about to be described. Tube 50 is fastened to the casting 246 by means of screws 247. 60

Casting 246 is held in place on block 245 by pins (not shown) which permit vertical movement only. As wear takes place shims may be inserted between the block and casting to compensate therefor. 65

Casting 246 supports a pipe elbow 251, one end of which is connected by means of a pipe 252 to a source of supply for whatever gas may be suitable for preserving the articles being processed. This may be under pressure or not, depending on the 70 75

vacuum existing in the chambers. The other, or horizontal, end of the pipe elbow 251 communicates with the interior of the valve tube 51.

A pin 253, extending from the pressure pipe 5 elbow 251, is guided in a hole in casting 246. At the horizontal center line of the pipe elbow there is a threaded thick walled portion into which a small pin 254 is inserted. This pin fits within a spring containing cylinder 255 which is fastened 10 in a bore of the casting 246 by means of the set screw 256. The pin 253 has a hook at its right hand end in which the end of a coil spring 257 is inserted. The other end of the spring is inserted in a screw eye which extends through the end of 15 the spring cylinder, and is held by a nut on the screw portion of the eye. This construction makes it possible to adjust the spring tension with which the pipe elbow is urged toward the right.

Threaded on the horizontal portion 259 of 20 the pipe elbow 251 is a collar 263 having an in-turned beveled flange thereon which fits into a recess of a similar collar which is in turn screwed to a tube 264. Tube 264 has a flange at its left hand end, which flange is beveled to cooperate 25 with a similar bevel on a tube 270 fixed within the outer valve tube 50. Tube 264 also has a reduced diameter portion near its right-hand end on which the hub of worm wheel 265 is mounted. At the far left end of tube 264 there is a pin which 30 extends through the tube, and into a short tube section 241, which tubular section is in turn riveted to the right-hand end of tube 51. Worm wheel 265 meshes with a worm 275 on the shaft 276 which is driven in the manner indicated 35 above. It will be seen that the spring tension exerted on the pipe elbow 251 tends to draw the beveled edges of tubes 264 and 270 together to form a pressure-tight joint between the pipe elbow and tube 51 while providing for rotation of 40 the tube 51 under drive of the worm wheel 265.

Door operating mechanism

It will be obvious from the above description that it is intended to place containers to be evacuated and gassed in chambers 63 at the left of the machine, and to remove these containers, after they have been operated upon in the manner indicated, at the right-hand end of the machine. During the interval when the chain links 56, and consequently the chambers 63, are passing over the rotating valve mechanism described, these chambers must be closed and air-tight.

Mechanism for causing closing of the doors 64 of the chambers 63, latching them closed, and unlatching and reopening them, is described below.

Supported on the body portion 57 of each chain link 56 is a hinge 76 (Fig. 7) on which is rotatably mounted the door or gate 64, which door comprises substantially one entire side of the evacuating chamber 63. Door 64 is normally held in its closed position by means of the combination right and left-hand coil spring 80 (Figs. 4 and 6) located on the hinge pin with its ends bearing against the link body portion 57. Formed in the middle of the spring, between the right and left hand coils, is the inverted U-shaped portion which engages the arm 77 integral with the bottom of the door 64. This arm 77 carries a roller which bears against a rod 78 (Figs. 4 and 6) 70 extending longitudinally of the machine and fastened to the casting 42. The rod 78 is bent in J-shape, the short end of the J being inserted in a hole in the upper portion of casting 42, and fixed therein by means of a set screw 79 (Fig. 6). 75 The long arm of the J of rod 78, as it extends to-

ward the left (Fig. 4) is bent upwardly and inwardly as shown in Figures 4 and 6.

As link 56 is moved to the right, the roller of arm 77 will make contact with the outer (Fig. 6) surface of rod 78, and as the link continues to advance the rod will force the lever downwardly until the gate or door 64 is fully open which will occur at approximately the time that the link 56 is opposite the casting 42 (Fig. 4). Shortly thereafter, the roller on the end of arm 77 will pass from beneath the rod 78, and the hinge spring 80 will cause the door to shut. The door will be retained in its closed position during the evacuating of the container by virtue of the atmospheric pressures on the outside of the door and the pressure of the spring 80 and the vacuum pull on the inside of the door. A tight seal is created by the soft rubber gasket 63¹ located in the edge of the chamber 63. When the link has passed from the suction or evacuating portion of the apparatus to the pressure applying portion, the door must be held shut against pressure. For this purpose the mechanism shown in Figs. 10, 11 and 12 is provided.

Door latching mechanism

The mechanism for latching the doors is shown in connection with the particular form of chamber 63 of Fig. 8; it is obvious that this mechanism is equally applicable to any form of chamber as, for example, that shown in Figs. 6 and 7.

Mounted in a hole in the thick walled top of chamber 63, Figs. 10, 11 and 12, is a shaft or stud 81 on which a bell crank 82 is rotatably mounted. The vertical arm of the bell crank 82 is provided with a cam following roller 84 for cooperation with a cam 83 suitably mounted on the frame of the machine in position to operate the bell crank just prior to the passage of the link-borne chamber 63 into the pressure applying zone. The horizontal arm of the bell crank 82 has a beveled end which is adapted to cooperate with a latch plate 85 integral with the door 64. Integral with the vertical arm of the bell crank 82 is an extension in which a pin 86 is inserted and pressed downwardly by a spring 87 extending between the shoulder on the pin and a screw 88 inserted in the hole. This pin cooperates with a depression in the wall 63 of the chamber to act as a detent and hold the bell crank in the position shown in Figs. 10 and 11. When the cam 50 follower roller 84 strikes the cam 83 the bell crank 82 is caused to rotate through a 90° angle taking the position shown in Fig. 12 and latching the door closed, the edges of the door seating against a gasket such as that shown at 63¹ in 55 Fig. 7.

The bell crank remains in the position of Fig. 12 until the container has been filled with gas and sealed, at which time the link 56 will have moved to the right and will be adjacent to the end of tube 50. Suitably mounted on the machine frame at this point is another cam 90 which, as the link continues to move, is contacted by the cam follower 84 and causes the arm of the bell crank to rise and return to its normal 65 position, unlatching the door 64, said door then being opened as already described in connection with Fig. 7 so that the operator may remove the gas filled and sealed container.

Container sealing mechanism

It is obvious that after the containers have been evacuated and gassed, they must be sealed before removal from the chamber 63. There are many common ways of sealing containers, as.

for example, capping them with crown caps, spinning tops thereon, etc. For purposes of simplicity, the containers shown in Figs. 8 and 9 are bottles or cans which are sealed by the application of crown caps. The chambers 63 of Figs. 8 and 9 are shown with mechanism for performing this sealing operation.

Each chamber 63 has a cylindrical, projecting portion integral with the top thereof. Through a hole in this projection a plunger 91 is inserted, this plunger being surrounded by the packing 92 inserted in the hole and held in place by the packing nut 93. At the top of the plunger a head 94 is riveted. Between the packing nut and the head 94 a coil spring 95 is compressed. Mounted on the head 94 is a cam follower 96 which cooperates with a cam rail 97 which is supported in any suitable manner from the frame of the machine.

Fastened to the bottom of the plunger 91 is a cap holding member 98 adapted to resiliently retain a single crown cap.

Just prior to the passage of the link into the evacuating zone, or, in other words, during the interval while the door 64 is open, the operator places the container to be evacuated within the chamber, and likewise places a crown cap in the member 98. When a link reaches the cam rail 97, the cam follower moving along that rail causes depression of the plunger 91 and downward movement of the crown cap on to the container top. As the follower continues to move along the rail, pressure is exerted to force the cap on to the container top, sealing the container. Additional movement of the link 56 causes the cam follower 92 to move upward under pressure of the spring 95, removing the cap member from the applied cap. At about this time the door latching mechanism described above permits the door to open, and the operator can then remove the evacuated, gassed, and sealed container.

Additional synchronizing means

An alternative or additional means for assuring synchronization of the movement of the chain link 56 with the rotation of the inner valve tube 51 is provided, this mechanism comprising rack segments on each of the chain links cooperating with gears driven from the main power source. This alternative synchronizing method is shown in detail in Figs. 8 and 9. It is to be understood that the mechanism is provided in duplicate, one on either side of the machine, although this is not shown in Figs. 8 and 9 since Fig. 9 is a broken, transverse section showing but one side of the machine.

The body 57 of each link 56 has fastened thereto on either side, a rack segment 301. The rack segments of the successive links form in effect a continuous rack. Fixed at any suitable point along the machine, and fastened to the outer channels 39 and 41, are castings 303 which serve to support shafts 305 and stub shafts 307. Mounted on the upper end of shaft 305 is a spur gear 310. At the lower end of shaft 305 is a spiral gear 312. Mounted on the stub shaft 307 is an idler gear 314 which engages both the rack segment 301 and the gear 310. Fixed for rotation with shaft 55 and in position to mesh with the spiral gear 312 is spiral gear 316.

As shaft 55 rotates it causes rotation of shaft 305, gears 310 and 314, and movement of the rack segment to assure movement of the links 56 along the tube 50 at a definite rate.

The worm wheels, gears, and rack segments are so proportioned that the chain links are moved at exactly the same rate as that at which a roller, if placed in the helical groove of tube 51, would advance longitudinally of that tube.

The foregoing material has described the mechanism as set forth in the co-pending application hereinbefore mentioned. The new improvements which have been mentioned briefly hereinabove are described below; the portion of the mechanism to which these improvements have been made being indicated by the various headings.

Chain drive mechanism

In some instances it is desirable that the links 56 have an intermittent motion rather than the continuous motion described hereinabove. This is particularly true when the valve mechanism is to be sealed tightly under pressure during a portion of the evacuating operation, whatever the mode of sealing may be, although one manner of causing such sealing is described hereinafter. When the drive is to be intermittent a Geneva movement such as that shown in Figs. 20 and 21 is supplied. The sprocket wheels 111 and 112 and the shaft 113 on which they are mounted, are driven through the medium of a pinion 185 mounted on an extension of the shaft 113. This pinion meshes with a gear 184 which is fixed on a stub shaft mounted in a bracket 183 which is supported from the framework 101 in the manner shown in Fig. 21. The shaft of gear 184 carries at its opposite or forward end a Geneva wheel 182 which is caused to rotate through 90 degrees during each revolution of the Geneva roller 181, which is in turn fixed to a disc 180 mounted on a second stub shaft, likewise supported in the bracket 183. Mounted on this second stub shaft is a pulley which is driven by a belt such as 124 from the motor 109 in the same manner as shown in Fig. 1.

It will be obvious from the above that during each rotation of the pulley the Geneva roller drives the Geneva wheel through a 90 degree arc, causing a movement of the shaft 113 and the sprockets 111 and 112 proportional to this 90 degree arc of movement of the wheel. In the present instance the gears are so proportioned that the links 56 are displaced twelve spaces along the valve mechanism during each revolution of disc 180; this gearing might, as is readily seen, be proportioned so that any desired number of spaces be moved through by a link during a single revolution of the disc.

The shaft 118, which was formerly driven by the pulley, is now driven through the gear 115 and pinion 119 which is on the shaft 118. The spiral gears 121, 122 and 133, 134 serve, as before, to transmit motion from the shaft 118 to the longitudinal drive shafts 53 and 55 and the spur gear 120 serves to transmit motion to the gear 177 (see Fig. 6) and through it and other mechanism transmits motion to the valve mechanism.

Valve mechanism

The form of valve mechanism previously discussed may be somewhat modified to reduce frictional losses in the machine and to reduce the vacuum loss through possible leaks occurring in the rotating inner tube structure previously described. In a modified form of valve mechanism a thick walled outer tube 50 (Figs. 13 and 14) is supplied in place of the relatively thin walled

tube 50 of Figs. 1 through 7. Inserted in the tube 50 are poppet valves 160 which extend longitudinally in a line along the uppermost surface of the tube 50 and have passages which communicate with the passages 62 in the links 56. The stems 162 of these valves cooperate with an inner valve tube 73 which replaces the valve tube 51. The tube 73 is considerably smaller in diameter than tube 50 and has on its outer surface a helical cam ridge 74 which as the tube is turned presses against the valve stems 162 successively to cause opening of the valves and admission of suction or pressure as the case may be to the passages 62 and application of suction or pressure 10 sure therethrough to the packages or containers within the chambers 63 of the links 56.

The construction of poppet valve members is shown in detail in Figs. 15, 16 and 17. This construction is extremely simple, the valve comprising a cylindrical shell 160 in a spider of which (see Fig. 17) valve stem 162 is slidably arranged. Cooperating with a valve seat formed in this shell is a valve head 163 of the shape shown in Fig. 16, which in its lowermost position prevents passage of air or gas through the valve, but which when the valve stem is raised against the pressure of spring 164 is raised from its seat and permits air to flow from one side of the valve to the other.

30 The tube 73 is driven in much the same manner as was the tube 51 of the modification discussed in connection with Figs. 1 through 12. However, since the construction is slightly different it will be described briefly. Extending to the left of the tube 73 is a sleeve member which is slotted (as shown in Fig. 13), to receive pins 172, which pins pass through a sleeve and gear member 165 which is generally conical in form at its left hand end, and which seats against a 35 conical seat in the member 143, which member is screwed into a threaded portion of the outer tube 50. The gear portion of element 165 meshes with a worm wheel 175 on a shaft 176, causing rotation of this element in the same manner as 40 hereinbefore described. Seating in the conical portion of the element 165 is a conical extension of suction pipe 151, which pipe is held in position by means of studs 153 and 148 which are supported in the same manner as described in connection with Fig. 4 and are spring pressed to 45 the right to retain the conical portion of the pipe within the seat of the member 165.

It will be obvious from the above that suction is applied through the pipe 151 to the inner tube 55 73 and through holes in that tube to the space between the tube and the outer tube 50, so that as the inner tube rotates and the cam surface 74 causes the valves 160 to be progressively unseated, suction is continuously applied to the links of the 60 moving chain due to the fact that the valves are successively opened at the same rate as that at which the links progress along the outer tube.

Pressure seating mechanism

65 As has been indicated, it is sometimes desirable to cause the outer tube 50 to be pressed against the links 56 during at least a portion of the evacuating operation. This is desirable because it eliminates any loss of suction which might occur 70 due to leakage between the outer tube and the links in either the construction of Figures 1 through 12 or that of Fig. 13. This pressure applying mechanism is used only in combination with the intermittent drive previously discussed, 75 since it will be obvious that pressure applied up-

wardly against the links of the tube 50 would cause friction which would make it impossible to drive the machine continuously, and which would increase the wear on the tubes and links to such a degree that the machine would no longer be practical. Since the pressure applying mechanism is used only in combination with the intermittent drive the times of application of pressure can be controlled by means of the driving mechanism. This is done in the following manner:

Integral with or fastened to the disc 180 is a drum 186 having two cam surfaces cut therein, one of which cooperates with a pair of electrical contacts 187, and the other with a pair of contacts 188. During each rotation of the disc each 15 pair of contacts is closed for an interval of time. One of these pairs of contacts controls an electromagnet 189 which when it operates causes opening of the valve 190, which in turn establishes communication between a pressure supply line 191 20 and a distributing line 192 (Fig. 20). Pressure in the line 192 is applied beneath a piston 193 (Fig. 13), which piston lies within a cylinder 66 similar to the cylinder 66 of Figures 1 through 12. As in the former instance, there is within 25 the cylinder a spring 68 which in this instance, however, bears against the outer tube 50 to hold it normally upward against the bottoms of the links with a limited spring pressure. It will be obvious that when pressure is applied to 30 the bottom of the piston 193 it rises in the cylinder 66, causing compression of the spring 68 and exerting a much increased pressure against tube 50 to hold it against the links. The cam cooperating with contacts 187 is so formed that 35 pressure is admitted to the pipe 192 only during the interval while the Geneva roller is not within a slot of the Geneva wheel and the chain of links is consequently stationary. Just prior to the entrance of the roller 181 into a slot of the 40 Geneva wheel 182, the contacts are opened and the valve 190 operated to shut off the air pressure and cause exhaust of the air in the pipe 192 and the various cylinders 66 to atmosphere.

Modified capping mechanism

When the mechanism described immediately above is utilized, it is necessary in order to secure the advantages of high vacuum that the containers be capped during a time when pressure 50 is applied to the line 192 and the vacuum applied to the containers is consequently of its highest value.

The above capping mechanism described in connection with Figs. 8 and 9 is not adapted to 55 this usage since that mechanism caps the containers during movement of the links. The capping mechanism shown in Fig. 20 is, therefore, substituted for that of Figs. 8 and 9 when the apparatus described immediately above is to be 60 used.

Mounted on the outer channel member 41 are the brackets 285 which extend upwardly and carry in bearings at the upper ends thereof a shaft 286. The shaft 286 has mounted on it 65 between the upper ends of the brackets, a bell crank 287 and has likewise mounted on it at either end arms 288. The arms 288 extend toward the center of the machine and carry at their ends a bar 289 which lies above the path of 70 movement of plungers 91 of the chambers 63, which plungers carry caps for capping containers and are identical with those shown in Figs. 8 and 9, except that it is unnecessary for them to be provided with rollers 96. Extending down- 75

wardly from the outwardly extending arm of bell crank 287 is a rod 302 which is connected to the piston rod of a "Hannifin" air cylinder, which cylinder is supported from the channel member 41 in any convenient manner. The operation of this cylinder is controlled by the second cam portion of disc 180 through the medium of the contacts 187, a solenoid 289, and a valve 290. The valve 290 controls admission of fluid from the supply line 191 to the lines 291 and 292, which lines are connected to the cylinder one at either side of the piston thereof. It will be seen that as the disc rotates during a portion of each revolution the solenoid is energized and air is supplied to the lower side of the piston, causing the piston rod to rise and force the bell crank 287 to rotate, thus causing the arms 288 to likewise rotate and to press the bar 289 downwardly against the plungers lying beneath it to cause capping of the containers in the chambers with which these plungers are associated. In the present instance the bar 289 extends over twelve plungers, thus capping twelve containers at once. It will be remembered that with the intermittent drive as described above twelve link spaces are moved over during each rotation of the pulley. While any other number of link spaces might be moved over, it will be obvious that the bar 289 should cover the same number of plungers as spaces are traversed in a single rotation of the pulley. The two cams are arranged so that slightly prior to the release of pressure on pistons 193 the bar 289 descends and performs the capping operation.

35 The intermittent drive and capping mechanism above described, as well as the pressure seating arrangement also above described may be used in connection with the valve mechanism of Figs. 13 and 14, as well as with valve mechanism of Figs. 1 through 12, since in either case the intermittent movement and the simultaneous capping is made necessary only because of the pressure seating arrangements hereinabove described and there is nothing in the construction of the valve mechanism of Figs. 1 to 12 which prevents use of the pressure seating arrangement therewith.

Modified link structure

In the link structure shown in Figs. 1 through 12, and particularly in Fig. 7, the portion 57 of the link which traverses the outer valve tube 50 is solid, and has a passageway extending from its lower to its upper surface through which pressure, either positive or negative, may be applied to the chamber 63. This construction is adequate in most instances, but since there is a possibility of sagging of the tube 50 or other slight misadjustment of parts causing a leak to occur between the lower surface of the portion 57 and the tube, a modified form of link shown in Figs. 18 and 19 has been devised. In this form the portion 57 is split, leaving two portions 57^a and 57^b (Fig. 19) between which a soft rubber gasket 140 is inserted. In addition, the portion 57^b is made slightly smaller so that instead of bearing against the side pieces 59 of the links it is free to move slightly with respect thereto. Likewise, there is inserted in the upper portion of the passage 62 a tube 62^a which extends downwardly through the soft rubber and carries at its lower end a washer 62^b having a spherically curved lower surface which fits into a similarly curved depression in the portion 57^b. This construction makes it possible for the portion 57^b to rotate slightly in

any direction without permitting a leak to occur between the valve tube and the link structure. Since the rubber 140 is inserted between the two portions 57^a and 57^b under compression it will be obvious that movement of the portion 57^b will cause added compression of the soft rubber in part of its area and a lessened compression in another part, the give of the rubber being sufficient to insure that it will expand to at least as great an extent as there is possible movement of the piece 57^a.

While the above has described preferred embodiments of my invention and in many instances various forms of these embodiments, it is to be understood that I do not limit myself to the form shown and described, nor the combinations of forms particularly pointed out since the various mechanisms may be used in different combinations and other mechanisms devised to perform the same functions. The scope of my invention is, therefore, to be limited only by the appended claims.

What I claim is:

1. In a mechanism for applying positive or negative pressure to the links of a moving chain, the combination of a rotary pressure control mechanism, links adapted to be moved along said mechanism, means for applying pressure to said mechanism, passageways in the links communicating with said pressure applying means through said pressure control mechanism, and means for operating said control mechanism in synchronism with the movement of said links.

2. A vacuum or suction applying mechanism, comprising an outer valve tube having a plurality of longitudinally spaced openings along the upper surface thereof, a second valve tube rotatably mounted within said first tube and resiliently pressed upwardly to form an air-tight seat therewith, a helical groove in the surface of said second tube, passages from the interior of said second tube to said helical groove, means for rotating said second tube, and means for applying suction to the interior of said second tube during rotation thereof.

3. A vacuum or suction applying mechanism, comprising a valve tube having longitudinally spaced openings therein, a second valve tube arranged to form a vacuum seat with said first tube and to rotate within said tube, a helical groove in the surface of said second tube, communicating passages from the interior of said second tube to said helical groove, means for rotating said second tube, and means to apply suction or vacuum to said second tube during the rotation thereof, whereby suction is applied progressively to said spaced openings.

4. A vacuum or suction applying mechanism, comprising an outer valve tube having longitudinally spaced openings therein, a second valve tube adapted to form a vacuum seat with said first tube and to rotate within said tube, a helical groove in the outer surface of said second tube, said groove having a pitch such that a group of said longitudinal openings lies between corresponding points of successive turns of said helix, passageways from the interior of said second tube to said groove, means for rotating said second tube, and means for applying suction internally of said second tube during rotation thereof whereby suction is applied progressively to corresponding ones of the openings of the various groups.

5. A vacuum or suction applying mechanism, comprising an outer valve tube having a plu-

rality of longitudinally spaced openings therein, a second valve tube adapted to form a vacuum seat with said first tube and to rotate within said tube, a helical groove in the outer surface of said 5 second tube, said groove having a pitch such that a group of said longitudinal openings lies between corresponding points of successive turns of said helix and having a width such that a plurality of holes less than the number in a group 10 is covered thereby, passages from the interior of said second tube to said groove, means for rotating said second tube, and means for applying suction internally of said tube during rotation thereof whereby suction is applied progressively 15 to corresponding pluralities of openings of said several groups.

6. In a mechanism for applying suction to the links of a moving chain, the combination of a tubular valve mechanism, links adapted to be 20 moved along said valve mechanism, means for applying vacuum to the interior of said valve mechanism, passageways in said links communicating with the interior of said valve mechanism, and means to operate said valve mechanism in 25 synchronism with the movement of said links.

7. A vacuum or suction applying mechanism, comprising a tube having valve members longitudinally spaced therealong, a second tube arranged within said first tube and adapted to rotate, a helical cam surface on the exterior of 30 said second tube to cooperate with said members, passages from the interior of said second tube to the space between said tubes, means for rotating said second tube, and means to apply suction 35 or vacuum to said second tube during rotation thereof whereby suction is applied continuously to the valve members and the valve members are progressively operated to apply suction in like manner to the exterior of the first mentioned tube.

8. A vacuum or suction applying mechanism, comprising an outer tube having longitudinally spaced valve elements therein, a second tube arranged to rotate within said first tube, a helical cam surface on the outer surface of said second tube, said surface having a pitch such that a group of said valve elements lies between corresponding points of successive turns of said helix, 45 passageways from the interior to the exterior of said second tube, means for rotating said second tube, and means for applying suction internally of said second tube during rotation thereof whereby suction is applied continuously to all valve elements and corresponding ones of the 50 valve elements of the various groups are progressively operated.

9. A vacuum or suction applying mechanism, comprising an outer valve tube having a plurality of longitudinally spaced valve elements there- 60 in, a second tube adapted to rotate within said first tube, a helical camming surface on the exterior of said second tube, the helix of the center line of said surface having a pitch such that a group of said valve elements lies between corresponding points of successive turns of said 65 helix and the camming surface having such a width that a plurality of valve elements less than the number in a group may simultaneously be operated thereby, passages from the interior to the exterior of said second tube, means for rotating said second tube, and means for applying suction internally of said tube during rotation thereof whereby suction is applied continuously to the valve elements and corresponding pluralities of said elements are operated progres- 70

sively to permit transmission of suction to the exterior of said first tube.

10. In a mechanism for applying suction to the links of a moving chain, in combination, an outer valve tube having a plurality of longitudinally spaced openings therein, a second valve tube adapted to form a vacuum seat with said first valve tube and to rotate within said tube, a helical groove in the outer surface of said second tube, said groove having a pitch such that a group of said longitudinal openings lies between corresponding points of successive turns of said helix and having a width such that a plurality of openings less than the number in a group is covered thereby, passages from the interior of said second tube to said groove, means for rotating said second tube whereby the interior of said tube progressively communicates with corresponding pluralities of openings of the several groups of openings, links arranged in chain formation and adapted for movement longitudinally of said outer tube in synchronism with the rotation of said inner tube, each said link comprising a body portion of a length equal to or less than that of a group of openings, a passageway within each link, said passageway having a longitudinal opening covering a plurality of openings equal to that covered by the width of the helix, and means for resiliently pressing said links and outer valve tube together whereby each 25 link is constantly in communication with the interior of said inner tube during the traverse of the outer tube.

11. In a mechanism for applying suction to the links of a moving chain, in combination, an outer tube having a plurality of longitudinally spaced valve mechanisms therein, a second tube adapted to rotate within said first tube, a helical camming surface on the exterior of said second tube, said camming surface having a pitch 35 such that a group of said valve mechanisms lies between corresponding points of successive turns of said helix and having a width such that a plurality of mechanisms less than the number in a group is simultaneously operable thereby, 40 a source of vacuum communicating with the space between the interior of the first said tube and the exterior of the second tube, means for rotating said second tube whereby progressive operation of corresponding mechanisms of the 45 several groups of mechanisms occurs, links arranged in chain formation and adapted for movement longitudinally of said outer tube in synchronism with the rotation of said inner tube, each said link comprising a body portion 50 of a length equal to or less than that of a group of openings, a passageway within each link, said passageway having a longitudinal opening of substantially the width of the mechanisms adapted for simultaneous operation by a turn of the 55 helix of the camming surface, and means for resiliently pressing said links and outer valve tube together whereby each link is constantly in communication with said vacuum source during the traverse of the outer tube.

12. In a suction or vacuum applying mechanism, in combination, a tubular valve mechanism comprising an outer and an inner valve tube, means for resiliently pressing said inner valve tube into contact with said outer tube throughout their lengths, a plurality of links arranged in chain formation, each link being adapted to form a vacuum-tight seal with said outer valve tube, means to restrain said links from movement in the direction of a diameter of said tubes, and 70

75

resilient means for pressing said links and said valve mechanism against said restraining means.

13. In a machine of the class described, an intermittently operable chain of conveyor links, an intermittently operable tubular valve mechanism over which said links pass, means to continuously apply vacuum to said valve mechanism and through it to said links, means to normally press said valve mechanism against said chain of links, and means operable during time intervals in which said chain and valve mechanism are stationary to urge said valve mechanism against said chain with increased pressure whereby substantially the full effect of said vacuum applying means is transmitted to said links.

14. In a machine of the class described, an intermittently operable chain of conveyor links, each link comprising a chamber for a container to be evacuated and closure applying means operable upon said container, an intermittently operable tubular valve mechanism over which said links pass, means to continuously apply vacuum to said valve mechanism and through it to said links, means to normally press said valve mechanism against said chain of links, means normally inoperative for actuating said closure applying means, means operable during time intervals in which said chain and valve mechanisms are stationary to urge said valve mechanism against said chain with increased pressure, and means operable momentarily at substantially the end of said stationary period for simultaneously actuating a plurality of said closure applying means.

15. In a machine of the class described, in combination, a rotary valve control mechanism, a plurality of links arranged in an endless chain formation and adapted to traverse said valve mechanism and to cooperate therewith, means to drive said chain and said mechanism synchronously, said means comprising a Geneva movement for supplying intermittent motion, and a gear train for producing proper rates of operation.

16. In a machine of the class described, in combination, a chain of conveyor links, a tubular valve mechanism over which said links are adapted to pass, means comprising a Geneva movement including driving and driven members for causing intermittent operation of said links and valve mechanism, means to normally press said valve mechanism against said links, and means operable by the continuously rotating driving member of said Geneva movement to cause said valve mechanism to be urged against said links with increased pressure during that portion of each rotation of the driving member in which it is not driving the driven member.

17. In a machine of the class described, in combination, a chain of conveyor links, a tubular valve mechanism longitudinally of which said links are adapted to pass, each link comprising a chamber for a container to be evacuated and closure applying means operable upon said container, means comprising a Geneva movement including driving and driven members for causing intermittent operation of said links and valve mechanism, means for causing operation of said closure applying means, and means under control of the continuously rotating driving member of said Geneva movement for causing energization of said closure applying means during an instant just prior to the driving of said driven member by said driving member.

18. In a machine of the class described, an intermittently operable chain of conveyor links, an

intermittently operable tubular valve mechanism over which said links pass, means to continuously apply vacuum to said valve mechanism and through it to said links, means to normally press said valve mechanism against said chain of links, and means operable during time intervals in which said chain and valve mechanism are stationary to urge said valve mechanism against said chain with increased pressure, said means comprising a continuously rotating cam drum, contacts operable thereby, a solenoid energized by closure of said contacts, a fluid control valve operated by said solenoid, and a fluid operated piston operating against said valve mechanism.

19. In a machine of the class described, an intermittently operable chain of conveyor links, each link comprising a chamber for a container to be evacuated and closure applying means operable upon said container, an intermittently operable tubular valve mechanism over which said links pass, means to continuously apply vacuum to said valve mechanism and through it to said links, means to normally press said valve mechanism against said chain of links, means normally inoperative for actuating said closure applying means, means operable during time intervals in which said chain and valve mechanisms are stationary to urge said valve mechanism against said chain with increased pressure, and means operable momentarily at substantially the end of said stationary period for simultaneously actuating a plurality of said closure applying means, said last mentioned means comprising a continuously rotating cam drum, contacts operated thereby, a solenoid energized by closure of said contacts, a fluid control valve operated by said solenoid, and a fluid operated piston arranged to operate said closure applying means.

20. In a mechanism of the class described, the combination of a tubular valve mechanism, links arranged in an endless chain and adapted to communicate with a pressure or suction source through the medium of said valve mechanism, said chain links comprising vacuum and pressure-tight chambers, means to permit the insertion of packages to be evacuated and filled within said chambers, means for automatically closing said chambers during evacuating and filling operations, means for sealing containers within said chamber, and means for automatically opening said chambers to permit removal of evacuated, filled and sealed packages.

21. In a machine of the class described, in combination, a tubular valve mechanism comprising an outer and an inner valve tube, means for resiliently pressing said inner valve tube into contact with said outer tube throughout their length, a plurality of links arranged in a continuous chain, means to drive said chain so that the links thereof pass successively over said tubular valve mechanism, and auxiliary means for driving each link of said chain while passing over the valve mechanism, said auxiliary means comprising helically grooved shafts extending along said mechanism and rollers on said links extending into the grooves of said shafts.

22. In a machine of the class described, in combination, a tubular valve mechanism comprising an outer and an inner valve tube, means for resiliently pressing said inner valve tube into contact with said outer tube throughout their lengths, a plurality of links arranged in a continuous chain, means to drive said chain so that the links thereof pass successively over said tubular valve mechanism, and auxiliary means for

driving each link of said chain while passing over the valve mechanism, said auxiliary mechanism comprising rack segments on said links and gears driven synchronously with said valve mechanism 5 cooperating with said rack segments.

23. A vacuum and pressure applying mechanism, comprising an outer valve tube having a plurality of longitudinally spaced openings therein, a second valve tube adapted to form a vacuum seat with said first tube and to rotate therein, a helical groove in the outer surface of said second tube, said groove having a pitch such that a group of said longitudinal openings lies between corresponding points of successive turns 10 of the helix, and having a width such that a plurality of holes less than the number in a group is covered thereby, passageways from the interior of said second tube to said grooves, a separating member within said second tube, 15 means for rotating said second tube, means for applying suction internally of said second tube at one end thereof, and means for applying pressure to the other end of said second tube during rotation thereof, whereby first suction and 20 then pressure is applied progressively to corresponding pluralities of openings of said several groups of openings of said first valve tube.

24. A vacuum and pressure applying mechanism, comprising an outer valve tube having longitudinally spaced openings therein and having a member separating one end from the other, a second valve tube extending within said first tube and abutting said member, said second tube being adapted to form a vacuum seat with said 30 first tube and to rotate therein, a third valve tube extending within said first tube and abutting said member on the other side thereof, said third valve being adapted to form a vacuum seat with said first tube and to rotate therein, helical grooves in the outer surfaces of said second and third tubes, said grooves each having a pitch such that a group of said longitudinal openings lies between corresponding points of successive turns of said helices, passageways from the 35 interiors of said second and third tubes to their respective grooves, means for rotating said second tube and means for applying suction interiorly thereof, means for rotating said third tube in synchronism with said second tube, and 40 means for applying pressure interiorly of said third tube during rotation thereof, whereby first suction and then pressure is applied progressively to corresponding ones of the openings of the various groups of openings in the first said tube.

25. In a machine of the class described, the combination of a tubular valve mechanism, means for driving said mechanism, and a conveyor chain adapted to move longitudinally of said valve mechanism in synchronism therewith, said conveyor chain being formed of a plurality of links 45 each of which comprises a block having a curved

surface adapted to fit said tubular mechanism, a soft rubber gasket fixed to the block, a plate fixed to said gasket on the opposite side thereof, and a tube extending through said plate and gasket and having a spherically curved washer thereon, said washer being adapted to seat in a correspondingly curved surface in said block. 5

26. In a machine of the class described, the combination of a tubular valve mechanism, means for driving said mechanism, a chain conveyor 10 adapted to move longitudinally of said valve mechanism and means for driving said chain in synchronism with said valve mechanism, said means including helically grooved shafts extending along said valve mechanism at the 15 sides thereof, the conveyor chain being formed of a plurality of links each of which comprises a block having a curved surface adapted to fit said tubular mechanism, a chamber comprising a plate separated from said block by a soft rubber 20 gasket, a tube extending through said plate and gasket and terminating in a spherically curved washer adapted to fit in a spherically curved depression in the upper surface of said block, said depression having a central bore which extends 25 through the block and is adapted to communicate with said valve mechanism, and side plates fixed to said chamber plate and extending downwardly and beneath said shafts to restrain said link against upward movement, said side plates 30 also serving to hold said block in proper position on said valve mechanism.

27. In a machine of the class described, in combination, a tubular valve mechanism comprising a tube having valve members spaced longitudinally thereof, a second tube arranged within said first tube and adapted to rotate, a plurality of links arranged in a continuous chain, means to drive said chain so that the links thereof pass successively over said valve mechanism, and auxiliary means for driving each link of said chain 35 while passing over the valve mechanism, said auxiliary mechanism comprising helically grooved shafts extending along said mechanism and rollers on said links extending into the grooves of 40 said shafts.

28. In a machine of the class described, in combination, a tubular valve mechanism comprising a tube having valve members spaced longitudinally thereof, a second tube arranged within said first tube and adapted to rotate, a plurality of links arranged in a continuous chain, means to drive said chain so that the links thereof pass successively over said valve mechanism, and auxiliary means for driving each link of said 50 chain while passing over the valve mechanism, said auxiliary mechanism comprising rack segments on said links and gears driven synchronously with said valve mechanism cooperating with said rack segments. 55
